UNITED STATES PATENT OFFICE.

ROBERT S. PEELLE, OF HOLLIS, NEW YORK, N. Y., ASSIGNOR TO THE PEELLE COMPANY, OF BROOKLYN, NEW YORK, A CORPORATION OF NEW YORK.

ELEVATOR DOOR.

Application filed December 13, 1922. Serial No. 606,721.

To all whom it may concern:

Be it known that I, ROBERT S. PEELLE, a citizen of the United States, residing at Hollis, in the borough of Queens, city of New York, county of Queens, and State of New York, have invented certain new and useful Improvements in Elevator Doors, of which the following is a specification, reference being had therein to the accompanying drawings, which form a part thereof.

My invention relates to elevator doors, and more particularly to doors of the "pass type" wherein a door, or door section, closing a shaft opening at one floor will, when closed, occupy a position close to the wall of the shaft about the opening, and in its vertical opening or closing movement will be so guided as to have a horizontal component of movement away from or towards the shaft, so that during its opening movement it may, in part, pass or lap a portion of a closed door at the opening of the next floor of the building.

Heretofore there has been devised and extensively used, a door of this type embodying therein a single rail structure extending continuously through a shaft, which structure carries an automatically acting switch mechanism for imparting the desired movements to a door, or to a door section, and while such doors have operated satisfactorily, the opening and closing of the doors has been attended with considerable noise as a result of the engagement of a rapidly moving door with the automatically acting switch mechanisms. Furthermore, such switch mechanisms require considerable attention to keep them properly oiled, and in some instances such mechanisms have broken while in use, thus interfering with the operation of the doors until the broken parts have been replaced.

With the above conditions in mind, I have devised an elevator door of the pass type, wherein neither the rail structure, nor the guides co-operating therewith, require any movement aside from movement of a door or door section, to impart the desired horizontal component of movement to the door or door section, thus eliminating all noise of moving parts when actuating a door, and obviating the necessity for any attention to an elevator door installation other than that required by ordinary doors of the vertically sliding type.

In doors embodying my invention, I employ a single continuous guide rail structure extending throughout a shaft, the main guide rail of which includes a short length positioned closely adjacent the wall of the shaft intermediate the lintel and sill of each door opening, and other and long lengths thereof arranged parallel with the short length above referred to, but spaced therefrom within the shaft, said short and said long rail lengths being connected by obliquely extending rail lengths. The long rail lengths have gaps therein adjacent the lintel and the sill of each door opening to permit guide shoes which are normally disengaged from this portion of the guide rail, to pass into and from engagement therewith, this gap being occupied by a switch mechanism composed solely of immovable parts, co-operating with the guide shoes above referred to, for imparting the desired movement to said shoes and to the portion of the door adjacent same, into and out of engagement with said long lengths of guide rail.

Associated with each said switch mechanism is a short supplemental guide rail adjacent the sill or the lintel of each door, or both, which is adapted to be engaged by the guide shoe co-operating with the switch mechanism when the door is approaching or is in the closed position, the part of this rail section engaged by the shoe when the door is closed being in substantially the same vertical plane as the short length of the main guide rail. Said supplemental guide rail has an inwardly inclined section extending substantially parallel with the oblique section of the main guide rail for giving the desired horizontal component of movement to the portion of the door adjacent the sill or lintel. This short guide rail length will also serve to help hold the door close to the wall of the shaft when in the closed position, and the inclined section thereof will direct the movement of the door inwardly of the shaft and towards the switch mechanism immediately following the initial opening movement thereof.

One of the guide shoes of each door or door section must be so constructed as to co-operate with the main rail structure, the supplemental guide rail structure, and the switch mechanism, so as to ensure the automatic engagement and disengagement of

the guide shoe with these parts through the medium of the switch mechanism with the upward or downward vertical movements of the door, while the other guide shoe need 5 co-operate only with the main guide rail.

A door embodying my invention has the further advantage that the switch mechanism may be readily incorporated in the rail structure in the shop preparatory to installation, but may be conveniently modified while being installed, or while being assembled in the shop, to compensate for the variance in the distances between floors of different buildings or in the same building. Furthermore, the switch mechanism may be made of cast metal, thus ensuring accuracy in the guide flanges thereon, and uniformity in all such switch mechanisms so as to permit the standardization of the structure, and thus simplify both the production and the installation of the elevator door equipment.

The rail structure as installed will have the various guide rails thereon accurately positioned and immovable in relation to each other, thus presenting a single continuous unitary construction, the various parts of which are subject to but slight wear, and cannot become disarranged or broken in the normal functioning of the door. The switch mechanism and the guide shoes co-operating therewith are so formed as to ensure merely a sliding impact between these shoes and the co-operating parts of the guide rail structure and switch mechanism, thus contributing toward a substantially noiseless operation of the door, as well as materially reducing wear, and avoiding likelihood of breakage of parts.

43 The main guide, and the supplemental guide rails and the co-operating guide shoes upon the door are so formed as to hold the door in close proximity to the wall of the shaft when in the closed position, thus reducing fire hazard.

45 The trucking feature and the overhanging astragal, while desirable in a door embodying my invention, were not per se invented by me, merely forming parts of the combination hereinafter described.

55 In a structure embodying my invention, both of the shoes upon each door, or section, are continuously engaged with some portion of the guide rail structure, thus ensuring absolute control of the door, or each of its sections, at all times during either its opening, or closing, movement.

60 The invention consists primarily in an elevator door embodying therein a vertically movable section, guide rail structures extending vertically of a shaft along opposite sides of the door opening, each consisting of a main guide rail having a short rail length parallel with the wall of a shaft, 65 a long rail length parallel therewith and

spaced therefrom within the shaft, and an oblique connecting rail length, a supplemental guide rail consisting of a short rail length arranged on the same vertical plane as the short rail length of said main rail, 70 and an oblique section extending substantially parallel with the oblique length of the main rail, said long rail length of the main rail having a gap formed therein adjacent said supplemental guide rail, and a switch 75 mechanism arranged in said gap and fixed in relation to said main and said supplemental guide rail, and guide shoes adjacent the top and bottom of said door at each side thereof, one of said guide shoes co-operating with the adjacent supplemental guide rail, switch mechanism and long length of guide rail beyond said gap only, and the other of said guide shoes on the same side of the door co-operating with the adjacent main guide rail only; and in such other novel features of construction and combination of parts as are hereinafter set forth and described, and more particularly 80 pointed out in the claims hereto appended. 90

Referring to the drawings,

Fig. 1 is a condensed view in elevation from within an elevator shaft, showing an elevator door structure embodying my invention;

Fig. 2 is a view of the rail structure at one side of the door opening, with a door structure consisting of two oppositely movable sections shown therein in dotted lines;

Fig. 3 is a front view of a casting forming a part of the rail structure and switch mechanism;

Fig. 4 is a side view thereof;

Fig. 5 is a front view of the guide shoe carried by a door section and co-operating with the switch mechanism, the supplemental guide rail and a portion of the main guide rail;

Fig. 6 is a side view thereof;

Fig. 7 is a view similar to Fig. 5 showing the guide shoe co-operating with the main guide rail only; and

Fig. 8 is a side view thereof.

Like letters refer to like parts throughout the several views.

In the embodiment of my invention shown in the drawings, A indicates that wall of an elevator shaft towards the floors of a building, it being a practice in such shafts to have a series of vertically alined door openings therein, one at each floor. At B I have indicated the sill of one such door opening, at C the lintel of said opening and at D one jamb thereof.

In the drawings, I have shown a portion of the rail structure adjacent one door opening only, it being understood that this structure extends vertically throughout the shaft, the part thereof adjacent each opening being the same as that adjacent every other

opening, so as to provide a continuous rail structure throughout the shaft.

It is also apparent that if desired a pass type door need not be used to close every door opening, this type of door being necessary only where the space between floors is insufficient to receive the door or door section closing the openings at an adjacent floor.

10 Fireproof freight elevator doors are usually formed of two sections indicated at E and F in the drawings, so connected as to cause said sections to move vertically in opposite directions when opening or closing 15 the door, the connection between the door sections, shown at G in the drawings, passing over a pulley or sheave H, the axis of which is parallel to the wall of the shaft having the door opening therein.

20 This connection is made upon each side of a door, one end of each connection being secured to a bracket I adjacent the bottom bar of the frame of the lower door section, the other end of said connection being secured 25 to a hanger bar J connected to the lower door section adjacent the top bar of its frame.

This construction of door is old and well known in this art.

30 The lower section F is provided with a projecting plate, indicated in dotted lines at K in Fig. 2 of the drawings, which forms a part of the trucking feature of the door, and the section E is provided with a projecting 35 angular astragal L adapted to co-operate with said bar K in closing any gap along the meeting line of the two door sections.

Since the means embodying the rail structure carried by the two door sections is the same upon opposite sides of each door opening, in my further description of the invention I will limit myself to an explanation of the details as they exist upon one side of the door openings only, it being understood 45 that this mechanism is duplicated upon the other side. In the drawings, duplicate reference letters are applied to corresponding parts upon opposite sides of the door, it being understood that, particularly as to the guide shoes and switch mechanism, the corresponding parts upon one side of the door are reversed upon the opposite side, these parts being made right and left by reason of their different relations to the guide 50 rail structures upon opposite sides of the door.

The guide rail structure is composed of a wall angle consisting of abutting sections of angle iron, one flange c of which is secured 60 to the wall of the shaft closely adjacent the line of the jamb of the door openings, and the other flange c' of which projects within the shaft. Carried by this wall angle c—c' is a main guide rail structure, 65 which extends throughout substantially the

entire height of all the door openings in the shaft, and a supplemental guide rail structure and suitable switches adjacent the sill and the lintel of each door opening, the construction adjacent each door opening being 70 the same as that adjacent every other door opening.

I have in the drawings shown merely that portion of the structure adjacent one door opening, it being understood that the main 75 guide rail adjacent one door extends into, and forms a part of, the main guide rail structure adjacent the adjoining door opening, the portion of this rail co-operating with the upper section of the door at one 80 opening also co-operating with the lower door section at the door opening immediately above, and the rail co-operating with the other and lower door section also co-operating with the upper door section at the door 85 opening immediately below.

The main guide rail consists of a short rail length b extending parallel with the wall of a shaft at substantially the meeting point of the door sections E and F, and 90 above and below this meeting point for a short distance, a long rail length c parallel with said short rail length, but spaced therefrom within the shaft and terminating above said short rail length, and an oblique 95 connecting rail length d, said rail lengths c and d being located between the length b and the lintel of the door opening. A corresponding long rail length e and a corresponding oblique connecting rail length f 100 are located below said rail length b and toward the sill of the door opening. The rail length c is in substantial alignment with the rail length e adjacent the door opening above that shown, while the rail length e 105 is in substantial alignment with the rail length c at the opening immediately below that shown, so as to form a substantially continuous main guide rail structure throughout the shaft. The long lengths of 110 said main guide rail adjacent the sill and adjacent the lintel of each door opening, are spaced apart to form a gap g to receive the switch mechanism adjacent the sill and the lintel of each door opening, which 115 mechanism will be more fully described hereinafter.

The flange c' of the wall angle is cut away at α^2 , so that the inner edge thereof follows the line of the short rail length b and the oblique rail lengths d and f so as to permit 120 the necessary movement of the brackets I and the hanger bar J, which parts extend across the edge of the wall angle, but must have a horizontal component of movement with the 125 door sections during the opening and closing movement thereof.

Adjacent the lintel of each door opening is a supplemental rail structure consisting of a short rail length h approximating one-half 130

the length of the short rail length b and arranged in the same vertical plane therewith, and an oblique section i extending substantially parallel with the oblique section d and substantially co-terminous with the long rail length e .

A similar supplemental rail section consisting of a rail length j corresponding in construction and arrangement with the rail length h , but adjacent the sill of a door opening, and an oblique section k similar to the section i , substantially parallel with the oblique rail length f and co-terminous with the rail length e is also employed. One of said supplemental rail sections co-operates with the lower door section, and the other with the upper door section.

The switch mechanism for an upwardly movable door, or section, consists of a short rail length m positioned beyond the end of the rail length c and extending in substantial alignment with the section i of the supplemental guide rail structure. The switch referred to is that located above and adjacent the lintel C of the door. The switch for a downwardly movable door, or section, is located below and adjacent the sill B and consists of a short rail length n positioned below the end of the long rail length e and extending in substantial alignment with the section k of the lower supplemental guide rail structure. The rail length m at one door opening is associated with a rail length n at the opening immediately above, it being possible to bring these two lengths together, although for convenience they are spaced apart and a connecting short rail length o is employed, the length of which may be varied according to the distance between the lintel of the door opening at one floor and the sill of the opening at the floor immediately above. The short length o is connected directly to the flange a' of the wall angle.

The construction of switch described is employed because in the opening and closing of doors at adjacent floor levels, the upper section of one door crosses the plane of movement of the lower section of the door immediately above, and the lower section of one door crosses the plane of movement of the upper door section at the opening immediately below, thus necessitating a detached switch member co-operating with the supplemental rail section, but spaced away therefrom sufficiently to permit the passage of the shoes of a section of one door when thus crossing the plane of movement of a section of another door.

Preferably the supplemental rail structure and the end portion of the long rail length adjacent thereto, as well as the short rail length m , are formed of a single casting, thus ensuring the proper relation of these parts and avoiding the necessity for special and accurate workmanship and fitting of

parts in forming these various parts for different door openings.

Upon each side bar of each door section are two guide shoes, one of which, p , is adapted to co-operate with the supplemental guide rail structure, the switch mechanism and a portion of the long rail length of the main guide rail associated with an adjacent door opening, and the other of which, q , is adapted to co-operate with a portion of the short rail length b , one oblique portion d or f and the long rail length c or e adjacent the opening closed by the door carrying said shoe. The guide shoe p on the door section E is therefore located adjacent the top bar of the frame of this section, while the guide shoe q is adjacent the bottom bar of the frame thereof, this positioning of the guide shoes being reversed as to the door section F.

The shoe p has two oppositely disposed flanges p' and p'' thereon spaced apart to receive the guide rail between same. The faces of these flanges presented towards each other, are so shaped as to reduce the contact area to a minimum, and at the same time provide oppositely flared openings in the shoe as shown, to ensure the engagement and disengagement of the shoe when passing to and from the supplemental guide rail structure to the main guide rail structure through the medium of the switch mechanism.

The flange p'' is extended in the direction of movement of the shoe toward the switch mechanism, while the flange p' is extended beyond the flange p'' in the direction of movement of the shoe from the main guide rail to the supplemental guide rail through the medium of such switch mechanism. The top and bottom of each flange is brought to an edge as shown, the ends of the oblique section i , the short rail lengths m and n , and the ends of the long rail lengths c and e also being reduced to an edge so as to avoid an end impact of the guide shoes and the rail lengths during the movement of the shoe in either direction.

The flange p' is so positioned that when closing the door it will pass between the supplemental guide rail and the wall of the shaft, while the flange p'' is so positioned as to pass between the main guide rail and the supplemental guide rail under like conditions. Both flanges are inclined in the same direction, obliquely to the path of vertical movement of the door, and project from the door to an extent to ensure the engagement of one of these flanges with some portion of the guide rail structure, either main or supplemental, or switch, prior to the disengagement of the other flange with some other portion of said guide rail or switch.

Since the shoe q co-operates solely with the main guide rail, it is merely necessary to provide similar flanges q' and q'' upon opposite sides of this shoe, and to so form

the walls of said flanges presented toward each other that they are adapted to engage both the vertical sections of the main guide rail and the oblique section connecting said

5 vertical sections. Preferably, I provide said flanges q' and q^2 with surfaces q^3 and q^4 parallel with each other, and with opposite surfaces leading therefrom indicated at q^5 and q^6 , the former of which surfaces will

10 engage the vertical sections b and c or b and e , and the latter of which will engage the oblique sections d or f .

The ends of the guide rail lengths c or e adjacent each gap in the main guide rail

15 are bowed slightly as shown in Fig. 4, to accommodate the flange p^2 , which may have a slight movement toward said rail length after its initial engagement with the supplemental rail length i or k .

20 In the accompanying drawings, I have shown what is known as a flame angle r along opposite sides of each door section, which flanges when the door is in the closed position, will fit close to the wall of the

25 shaft or to the flange a of the wall angle, but are of a depth to pass the edges of the guide rails with the movement of the door toward or from the wall of the shaft.

Secured to the wall flange a' of each

30 guide rail structure are stops s adapted to be engaged by the hanger bar J when the door is in the fully open position, so as to hold the reinforced top of this section substantially flush with the sill B .

35 The lower section F is provided with a flame angle and toe guard t of the usual construction.

The guide rail structure and co-operating guide shoes upon the door sections may

40 be used in connection with full counterbalanced, semi-automatic, or full automatic doors, the manner of actuating the doors having no modifying effect in the functioning of said guide rails and said shoes.

45 The operation of the herein described mechanism is substantially as follows:

When a door is in the closed position, as shown more particularly in dotted lines in Fig. 2, the shoe q of the upper section will

50 be engaged with a portion of the short rail length b , and the shoe p will be engaged with the short length h of the supplemental guide rail structure, thus holding the door section close to the wall of the elevator

55 shaft. With the initial opening movement of the door, the upper section will, for a short distance, move in a vertical plane only, until the flanges p' and q' of the guide shoes of said section ride upon the oblique

60 rail lengths d and i respectively, whereupon the vertical movement will receive a horizontal component until the shoe q passes onto the rail length c , and the shoe p has passed the switch members $m-n-o$ and

engaged the rail section e adjacent the door

65 upon the adjoining floor. In passing from the rail length h to the length i , the flange p^2 will act upon said rail length i , the flange p' merely following the opposite surface of

said rail length.

70 By reason of the fact that the flange p^2 projects beyond the flange p' and is laterally deflected with relation to the vertical center line of the door, or to the wall of a shaft, the forwardly projecting end of

75 said flange p^2 will engage the short rail

length m of the switch while the oppositely projecting end of the flange p' is still in engagement with the rail length i , thus ensuring the engagement of one flange of the

80 shoe with the length m before the other flange has been disengaged from the supplemental guide rail. Before the flange p^2

85 has passed out of engagement with the switch m or o , the flange p' of that shoe

will have engaged the part m , thus limiting

movement of the door inwardly of the shaft.

Furthermore, the flange p' will simultaneously engage the rail lengths i and m and the rail lengths n and e with the same lim-

90 iting effect. After the flange p^2 has passed

from the rail length m and the short rail

length o , when such is used, it may have

95 a slight return movement as a result of the engagement of the flange p' with the short rail length n , but this return movement will be checked as a result of the engagement of the flange p^2 with the end of the long rail

length e immediately above.

This movement of the upper door sec-

tion will be the same with every door in a

shaft, the switch mechanism, however, act-

ing not only with relation to the upper door

section of one door, but with relation to the

lower door section of the door next above,

105 each of these doors when operated crossing

the plane of movement of the other door

when it is operating.

The lower door section will have exactly

110 the same movements as the upper door sec-

tion, except that it will move downwardly

instead of upwardly, the shoe q upon this

section passing from the short rail length b

115 along the oblique rail length f onto the ver-

115 tically extending rail length e . The shoe p

will pass along the short rail length j of

the supplemental rail structure and the

oblique portion k thereof until the project-

120 ing end of the flange p^2 engages the short

rail length n , thus causing the shoe q to pass

over the switch mechanism until said flange

125 p^2 thereof engages the end of the rail length

e at the floor next below. During the clos-

ing movement of the door the operation will

be the reverse of that described. In fact

125 the movement of the shoes p upon each door

section will be exactly the same as that upon

the other, since the parts are reversed, the

reversal of parts, however, being compensated for by the fact that the doors themselves move in opposite directions.

It will be observed that while each door section is guided in its opening and closing movements by a structure composed of stationary guide rails spaced apart as to some portions thereof to form gaps, that the different portions of said rails and the switch mechanism are so positioned with relation to each other as to permit a free sliding movement of the guide shoes of the door from one of the portions thereof to the other without impact or jar, thus ensuring not only perfect ease in the operation of the door, but avoiding the noise of moving parts and likelihood of breakage of any of the parts irrespective of the speed at which the door sections are moved.

It will also be observed that while the shoe *p* in its movements must pass the gaps in the guide rail and switch mechanism with which it co-operates, that the construction of the shoe is such that the effect secured is, nevertheless, that of a continuous guide rail, notwithstanding the presence of these gaps, the purpose of which is to permit different door sections to cross the plane of movement of another door section, such movement, however, being of necessity at different intervals. Hence, while the short rail length and the oblique sections of the main guide rail co-operate only with the doors at one opening in a shaft, the long rail lengths, more remote from the wall of the shaft, may and do serve to guide sections of doors at different openings.

The arrangement of the pulley or sheave with its axis parallel to the wall of the shaft permits the horizontal component of movement in each of the door sections without limiting the vertical movement thereof.

It is not my intention to limit the invention to the precise details of construction shown in the accompanying drawings, it being apparent that such may be varied without departing from the spirit and scope of the invention.

Having described the invention, what I claim as new and desire to have protected by Letters Patent, is:—

1. An elevator door embodying therein a vertically movable section, guide rail structures extending vertically of a shaft along opposite sides of the door opening, each consisting of a main guide rail having a short rail length parallel with the wall of the shaft, a long rail length parallel therewith and spaced therefrom within the shaft, and an oblique connecting rail length, a supplemental guide rail consisting of a short rail length arranged in the same vertical plane as the short rail length of said main rail, and an oblique section extending substantially parallel with the oblique length

of the main rail, said long rail length of the main rail having a gap formed therein adjacent said supplemental guide rail, and a switch mechanism arranged in said gap and fixed in relation to said main and said supplemental guide rail, and guide shoes adjacent the top and bottom of said door at each side thereof, one of said guide shoes co-operating with the adjacent supplemental guide rail, switch mechanism and long length of guide rail beyond said gap only, and the other of said guide shoes on the same side of the door co-operating only with the adjacent main guide rail.

2. An elevator door embodying therein two oppositely and vertically movable sections, guide rail structures extending vertically of a shaft upon opposite sides of each door opening in the shaft, each consisting of a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rails, and guide shoes adjacent the top and bottom of each of said door sections at each side thereof, the upper guide shoe of one of said sections and the lower guide shoe of the other of said sections, co-operating only with the adjacent supplemental guide rail, switch mechanism and a long length of guide rail at an adjacent door opening beyond said gap, and the other guide shoe on the same side of each of said door sections co-operating only with the adjacent main guide rail.

3. An elevator door embodying therein a vertically movable section, guide rail structures extending vertically of a shaft along opposite sides of the door opening, each consisting of a main guide rail having a short rail length parallel with the wall of the shaft, a long rail length parallel therewith and spaced therefrom within the shaft, and an oblique connecting rail length, a supplemental guide rail consisting of a short rail length arranged in the same vertical plane as the short rail length of said main rail, and an oblique section extending substantially parallel with the oblique length

and an oblique section extending substantially parallel with the oblique length of the main rail, said long rail length of the main rail having a gap formed therein adjacent said supplemental guide rail, and a switch mechanism including therein a short rail length in said gap extending in substantial alinement with the end of the oblique section of said supplemental guide rail, and between same and the end of said long rail length of the main guide rail at an adjacent door opening, and guide shoes adjacent the top and bottom of said door at each side thereof, one of said guide shoes co-operating with the adjacent supplemental guide rail, switch mechanism and long length of guide rail beyond said gap only, and the other of said guide shoes on the same side of the door co-operating only with the adjacent main guide rail.

4. An elevator door embodying therein a vertically movable section, guide rail structures extending vertically of a shaft along opposite sides of the door opening, each consisting of a main guide rail having a short rail length parallel with the wall of the shaft, a long rail length parallel therewith and spaced therefrom within the shaft, and an oblique connecting rail length, a supplemental guide rail consisting of a short rail length arranged in the same vertical plane as the short rail length of said main rail, and an oblique section extending substantially parallel with the oblique length of the main rail, said long rail length of the main rail having a gap formed therein adjacent said supplemental guide rail, and a switch mechanism including therein two short rail lengths in said gap extending in substantial alinement with the end of said oblique section of said supplemental guide rail, and the oblique section of a supplemental guide rail at an adjacent door opening, and between said oblique sections respectively, and the adjacent ends of said long rail lengths of the main guide rail at said adjacent door openings respectively, and guide shoes adjacent the top and bottom of each of said door sections at each side thereof, the upper guide shoe of one of said sections and the lower guide shoe of the other of said sections, co-operating only with the adjacent supplemental guide rail, switch mechanism and a long length of guide rail at an adjacent door opening beyond said gap, and the other guide shoe on the same side of each of said door sections co-operating only with the adjacent main guide rail.

6. An elevator door embodying therein a vertically movable section, guide rail structures extending vertically of a shaft along opposite sides of the door opening, each consisting of a main guide rail having a short rail length parallel with the wall of the shaft, a long rail length parallel therewith and spaced therefrom within the shaft, and an oblique connecting rail length, a supplemental guide rail consisting of a short rail length arranged in the same vertical plane as the short rail length of said main rail, and an oblique section extending substantially parallel with the oblique length of the main rail, said long rail length of the main rail having a gap formed therein adjacent said supplemental guide rail, and a switch mechanism including therein two short rail lengths in said gap extending in substantial alinement with the end of said oblique section of said supplemental guide rail, and the oblique section of a supplemental guide rail at an adjacent door opening, and between said oblique sections respectively, and the adjacent ends of said long rail lengths of the main guide rail at said adjacent door openings respectively, and a short rail length parallel with said long rail lengths respectively, positioned between the oblique rail lengths of said switch

5 10 15 20 25 30 35 40 45 50 55 60 65 70 75 80 85 90 95 100 105 110 115 120 125 130

- mechanism, and guide shoes adjacent the top and bottom of said door at each side thereof, one of said guide shoes co-operating with the adjacent supplemental guide rail, 5 switch mechanism and long length of guide rail beyond said gap only, and the other of said guide shoes on the same side of the door co-operating only with the adjacent main guide rail.
10. An elevator door embodying therein two oppositely and vertically movable sections, guide rail structures extending vertically of a shaft upon opposite sides of each door opening in the shaft, each consisting of a main guide rail having a short rail length parallel with the wall of the shaft, long rail lengths parallel therewith and spaced therefrom within the shaft and terminating adjacent the sill and the lintel 15 of the door opening respectively, and oblique connecting rail lengths, supplemental guide rails adjacent the sill and the lintel of the door opening, each consisting of a short rail length arranged on the same vertical plane as the short rail length of said main rail, and an oblique section extending substantially parallel with the adjacent oblique rail length of the main rail, the long rail lengths of the main rail at each door 20 opening being spaced away from the long rail lengths at adjacent openings above and below, to form a gap in said main rail between adjacent door openings, and switch mechanisms including therein respectively two short rail lengths in said gap extending in substantial alinement with the end of said oblique section of said supplemental guide rail, and the oblique section of a supplemental guide rail at an adjacent door 25 opening, and between said oblique sections respectively, and the adjacent ends of said long rail lengths of the main guide rail at said adjacent door openings respectively, and a short rail length parallel with said long rail lengths respectively, positioned between the oblique rail lengths of said switch mechanism, and guide shoes adjacent the top and bottom of each of said door sections at each side thereof, the upper guide 30 shoe of one of said sections and the lower guide shoe of the other of said sections co-operating only with the adjacent supplemental guide rail, switch mechanism and a long length of guide rail at an adjacent door opening beyond said gap, and the other guide shoe on the same side of each of said door sections co-operating only with the adjacent main guide rail.
8. An elevator door embodying therein a vertically movable section, guide rail structures extending vertically of a shaft along opposite sides of the door opening, each consisting of a main guide rail having a short rail length parallel with the wall of a shaft, 35 a long rail length parallel therewith and spaced therefrom within the shaft, and an oblique connecting rail length, a supplemental guide rail consisting of a short rail length arranged on the same vertical plane as the short rail length of said main rail, and an oblique section extending substantially parallel with the oblique length of the main rail, said long rail length of the main rail having a gap formed therein adjacent said supplemental guide rail, and a switch mechanism arranged in said gap and fixed in relation to said main and said supplemental guide rail, a guide shoe at each side of said door section co-operating with the adjacent supplemental guide rail, switch mechanism and long length of guide rail beyond said gap, consisting of oppositely disposed spaced guide flanges having surfaces thereon parallel with said short and said long rail lengths, and spaced surfaces thereon substantially parallel with the oblique sections connecting said long and said short rail lengths.
9. An elevator door embodying therein a vertically movable section, guide rail structures extending vertically of a shaft along opposite sides of the door opening, each consisting of a main guide rail having a short rail length parallel with the wall of a shaft, a long rail length parallel therewith and spaced therefrom within the shaft, and an oblique connecting rail length, a supplemental guide rail consisting of a short rail length arranged on the same vertical plane as the short rail length of said main rail, and an oblique section extending substantially parallel with the oblique length of the main rail, said long rail length of the main rail having a gap formed therein adjacent said supplemental guide rail, and a switch mechanism arranged in said gap and fixed in relation to said main and said supplemental guide rail, a guide shoe at each side of said door section co-operating with the adjacent supplemental guide rail, switch mechanism and long length of guide rail beyond said gap, consisting of oppositely disposed flanges spaced apart to receive said supplemental guide rail, said flanges being respectively inclined obliquely to the vertical with the opposite ends thereof projecting in opposite directions and extended beyond the end of the other flange to a position to ensure the engagement of one of said flanges with said switch mechanism and the main or the supplemental guide rail, according to the direction of movement of the door, and a second guide shoe on each side of the door section co-operating only with the adjacent main guide rail.
10. An elevator door embodying therein a vertically movable section, guide rail structures extending vertically of a shaft along

- opposite sides of the door opening, each consisting of a main guide rail having a short rail length parallel with the wall of the shaft, a long rail length parallel therewith and spaced therefrom within the shaft and an oblique connecting rail length, a supplemental guide rail consisting of a short rail length arranged in the same vertical plane as the short rail length of said main rail, and
- 5 10 15 20 25 30 35 40 45 50 55 60 65
- an oblique section extending substantially parallel with the oblique length of the main rail, said long rail length of the main rail having a gap formed therein adjacent said supplemental guide rail, and a switch mechanism arranged in said gap and fixed in relation to said main and said supplemental guide rail, a guide shoe at each side of said door section co-operating with the adjacent supplemental guide rail, switch mechanism and long length of guide rail beyond said gap, consisting of oppositely disposed flanges spaced apart to receive said supplemental guide rail, said flanges being respectively inclined obliquely to the vertical with the opposite ends thereof projecting in opposite directions and extended beyond the end of the other flange to a position to ensure the engagement of one of said flanges with said switch mechanism and the main or the supplemental guide rail, according to the direction of movement of the door, and a second guide shoe on each side of the door section co-operating only with the adjacent main guide rail, the ends of the flanges upon said first named guide shoes, and the co-operating ends of said main and said supplemental guide rails, being reduced in thickness.
12. An elevator door embodying therein two oppositely and vertically movable sections, guide rail structures extending vertically of a shaft upon opposite sides of each door opening in the shaft, each consisting of a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rails, a guide shoe at each side of each of said door sections co-operating with the adjacent supplemental guide rail, switch mechanism and long length of guide rail beyond said gap, consisting of oppositely disposed flanges spaced apart to receive said supplemental guide rail, said flanges being respectively inclined obliquely to the vertical with the opposite ends thereof projecting in opposite directions and extended beyond the end of the other flange to a position to ensure the engagement of one of said flanges with said switch mechanism and the main or the supplemental guide rail, according to the direction of movement of the door, and a second guide shoe on each side of each of said door sections, consisting of oppositely disposed spaced guide flanges having surfaces thereon parallel with said short and said long rail lengths, and spaced surfaces thereon substantially parallel with the oblique sections connecting said long and said short rail lengths.
13. An elevator door embodying therein

- a vertically movable section, guide rail structures extending vertically of a shaft along opposite sides of the door opening, each consisting of a main guide rail having
- 5 a short rail length parallel with the wall of the shaft, a long rail length parallel therewith and spaced therefrom within the shaft, and an oblique connecting rail length, a supplemental guide rail consisting of a
- 10 short rail length arranged in the same vertical plane as the short rail length of said main rail, and an oblique section extending substantially parallel with the oblique length of the main rail, said long rail length
- 15 of the main rail having a gap formed therein adjacent said supplemental guide rail, and a switch mechanism including therein two short rail lengths in said gap extending in substantial alinement with the end
- 20 of said oblique section of said supplemental guide rail, and the oblique section of a supplemental guide rail at an adjacent door opening, and between said oblique sections respectively, and the adjacent ends of said
- 25 long rail lengths of the main guide rail at said adjacent door openings respectively, a guide shoe at each side of said door section co-operating with the adjacent supplemental guide rail, switch mechanism and
- 30 long length of guide rail beyond said gap, consisting of oppositely disposed flanges spaced apart to receive said supplemental guide rail, said flanges being respectively inclined obliquely to the vertical with the
- 35 opposite ends thereof projecting in opposite directions and extended beyond the end of the other flange to a position to ensure the engagement of one of said flanges with said switch mechanism and the main or the
- 40 supplemental guide rail, according to the direction of movement of the door, and a second guide shoe on each side of the door section consisting of oppositely disposed spaced guide flanges having surfaces thereon parallel with said short and said long rail lengths, and spaced surfaces thereon substantially parallel with the oblique sections connecting said long and said short rail lengths.
- 45 14. An elevator door embodying therein two oppositely and vertically movable sections, guide rail structures extending vertically of a shaft upon opposite sides of each door opening in the shaft, each consisting of a wall angle extending vertically of the shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, said wall angle adjacent said short rail length and said oblique sections being cut away to permit movement of said means adjacent said rail
- 50 15. An elevator door embodying therein two oppositely and vertically movable sections, guide rail structures extending vertically of a shaft upon opposite sides of each door opening in the shaft, each consisting of a wall angle extending vertically of the shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, said wall angle adjacent said short rail length and said oblique sections being cut away to permit movement of said means adjacent said rail
- 55 16. An elevator door embodying therein two oppositely and vertically movable sections, guide rail structures extending vertically of a shaft upon opposite sides of each door opening in the shaft, each consisting of a wall angle extending vertically of the shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, said wall angle adjacent said short rail length and said oblique sections being cut away to permit movement of said means adjacent said rail
- 60 17. An elevator door embodying therein two oppositely and vertically movable sections, guide rail structures extending vertically of a shaft upon opposite sides of each door opening in the shaft, each consisting of a wall angle extending vertically of the shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, said wall angle adjacent said short rail length and said oblique sections being cut away to permit movement of said means adjacent said rail
- 65 18. An elevator door embodying therein two oppositely and vertically movable sections, guide rail structures extending vertically of a shaft upon opposite sides of each door opening in the shaft, each consisting of a wall angle extending vertically of the shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, said wall angle adjacent said short rail length and said oblique sections being cut away to permit movement of said means adjacent said rail

- lengths, stops carried by said wall angle in the path of movement of the means carried by the lower door section, and a truck bar carried by the top of said lower door section 5 and projecting through the door opening when the door is closed, and guide shoes adjacent the top and bottom of each of said door sections at each side thereof, the upper guide shoe of one of said sections and the lower guide shoe of the other of said sections, co-operating only with the adjacent supplemental guide rail, switch mechanism and a long length of guide rail at an adjacent door opening beyond said gap, and the other guide shoe on the same side of said door sections co-operating only with the adjacent main guide rail.

16. An elevator door embodying therein two oppositely and vertically movable sections, flexible connections between said sections, and sheaves about which said flexible connections pass, said sheaves having their axes extending parallel with the wall of the shaft adjacent the door opening, guide rail structures extending vertically of the shaft upon opposite sides of each door opening in the shaft, each consisting of a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, flexible connections between said means respectively, sheaves about which said flexible connections pass, the axes of said sheaves being parallel with the wall of the shaft adjacent the door opening, said wall angle adjacent said short rail length and said oblique sections being cut away to permit movement of said means adjacent said rail lengths, and guide shoes adjacent the top and bottom of each of said door sections at each side thereof, the upper guide shoe of one of said sections and the lower guide shoe of the other of said sections, co-operating only with the adjacent supplemental guide rail, switch mechanism and a long length of guide rail at an adjacent door opening beyond said gap, and the other guide shoe on the same side of said door section co-operating only with the adjacent main guide rail.

17. An elevator door embodying therein two oppositely and vertically movable sections, guide rail structures extending vertically of a shaft upon opposite sides of each door opening in the shaft, each consisting of a wall angle extending vertically of the

shaft and having secured thereto a main guide rail having a short rail length parallel with the wall of the shaft, long rail lengths parallel therewith and spaced therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an oblique section extending substantially parallel with the adjacent oblique rail length of the main rail, the long rail lengths of the main rail at each door opening being spaced away from the long rail lengths at adjacent openings above and below, to form a gap in said main rail between adjacent door openings, and switch mechanisms arranged in said gaps respectively, and fixed in relation to said main and said supplemental guide rail, means carried by each of said door sections, projecting across the edges of said wall angle and said rail lengths respectively, flexible connections between said means respectively, sheaves about which said flexible connections pass, the axes of said sheaves being parallel with the wall of the shaft adjacent the door opening, said wall angle adjacent said short rail length and said oblique sections being cut away to permit movement of said means adjacent said rail lengths, and guide shoes adjacent the top and bottom of each of said door sections at each side thereof, the upper guide shoe of one of said sections and the lower guide shoe of the other of said sections, co-operating only with the adjacent supplemental guide rail, switch mechanism and a long length of guide rail at an adjacent door opening beyond said gap, and the other guide shoe on the same side of said door section co-operating only with the adjacent main guide rail.

18. An elevator door embodying therein a vertically movable section, guide rail structures extending vertically of a shaft along opposite sides of the door opening, each consisting of a main guide rail having a short rail length parallel with the wall of the shaft, a long rail length parallel therewith and spaced therefrom within the shaft, and an oblique connecting rail length, a supplemental guide rail consisting of a short rail length arranged in the same vertical plane as the short rail length of said main rail, and an oblique section extending substantially parallel with the oblique length of the main rail, said long rail length of the main rail having a gap formed therein adjacent said supplemental guide rail, and a switch mechanism including therein a short rail length in said gap extending in substantial alignment with the end of the oblique

section of said supplemental guide rail, and between same and the end of said long rail length of the main guide rail at an adjacent door opening, said short rail length and the 5 adjacent ends of said long rail length of the main guide rail and said supplemental guide rail being integrally formed in a metal casting and guide shoes adjacent the top and bottom of said door at each side 10 thereof, one of said guide shoes co-operating with the adjacent supplemental guide rail, switch mechanism and long length of guide rail beyond said gap only, and the other of said guide shoes on the same side of the 15 door co-operating only with the adjacent main guide rail.

19. An elevator door embodying therein two oppositely and vertically movable sections, guide rail structures extending vertically of a shaft upon opposite sides of each door opening in the shaft, each consisting of a main guide rail having a short rail length parallel with the wall of the shaft, long rail lengths parallel therewith and spaced 20 therefrom within the shaft and terminating adjacent the sill and the lintel of the door opening respectively, and oblique connecting rail lengths, supplemental guide rails adjacent the sill and the lintel of the door opening, each consisting of a short rail length arranged in the same vertical plane as the short rail length of said main rail, and an 25 oblique section extending substantially parallel with the adjacent oblique rail length of the main rail, the long rail lengths of the main rail at each door opening being spaced away from the long rail lengths at adjacent 30 openings above and below, to form a gap in said main rail between adjacent door 35 openings, and switch mechanisms including therein respectively two short rail lengths

in said gap extending in substantial alignment with the end of said oblique section of said supplemental guide rail, and the oblique section of a supplemental guide rail 40 at an adjacent door opening, and between said oblique sections respectively, and the adjacent ends of said long rail lengths of the main guide rail at said adjacent door 45 openings respectively, guide shoes at each side of each of said door sections co-operating with the adjacent supplemental guide rail, switch mechanism and long length of guide rail beyond said gap, each of said 50 shoes consisting of oppositely disposed flanges spaced apart to receive said supplemental guide rail, said flanges being respectively inclined obliquely to the vertical 55 with the opposite ends thereof projecting in opposite directions and extended beyond the end of the other flange to a position to ensure the engagement of one of said flanges with said switch mechanism and the main or the supplemental guide rail, according 60 to the direction of movement of the section, and a second guide shoe on each side of each door section consisting of oppositely disposed spaced guide flanges having surfaces thereon parallel with said short and 65 said long rail lengths, and spaced surfaces 70 thereon substantially parallel with the oblique sections connecting said long and said short rail lengths.

In witness whereof I have hereunto affixed my signature, in the presence of two subscribing witnesses, this 6th day of December, 1922.

ROBERT S. PEELLE.
